(57) **CLAIM**

The ornamental design for a portion of a tote bag, as shown and described.

DESCRIPTION

FIG. 1 is a top, front perspective view of a portion of a tote bag showing our new design;

FIG. 2 is a top plan view thereof;

FIG. 3 is a front elevation view thereof;

FIG. 4 is a left side elevational view thereof;

FIG. 5 is a right side elevational view thereof; and,

FIG. 6 is a rear elevational view thereof.

The broken lines showing the remainder of the tote bag are for illustrative purposes only and form no part of the claimed design.
